UNITED STATES PATENT OFFICE.

OTTO A. BANNER, OF MILWAUKEE, WISCONSIN, ASSIGNEE TO THE FALK CORPORATION,
OF MILWAUKEE, WISCONSIN, A CORPORATION OF WISCONSIN.

OIL ENGINE.

Application filed July 11, 1925. Serial No. 42,925.

This invention relates to oil engines and particularly to engines of the type in which the fuel is introduced as sprays, into a chamber which is segregated from the piston space and communicates therewith through a restricted passage.

In my prior Patent No. 1,544,524, issued June 30, 1925, I have described an engine of the type mentioned in which the fuel is introduced in the form of opposed sprays which meet in a zone eccentrically disposed with respect to the restricted passage. By this eccentric relation between the fuel impact zone and restricted passage I have been able to utilize to a marked degree the turbulence set up in the chamber and passage during the working stroke to effect a combustible mixture of the air and fuel. This has resulted in an ability to effect a clean combustion of the fuel in quantities sufficient to obtain mean effective pressures as high as one hundred eleven pounds and more. In the engine shown in said patent the chamber is of somewhat symmetrical form, the restricted passage being arranged midway of the length thereof and concentric with the central axis of the piston space. The eccentric relation between the fuel impact zone and the restricted passage is effected in said engine by an unsymmetrical arrangement of the fuel sprays.

One object of the present invention is to further improve the combustion in engines of this type. This I have accomplished by arranging the restricted passage eccentrically of the axis of the piston space. With a centrally disposed restricted passage the gases, flowing through the passage during the working stroke, spread uniformly in all directions within the piston space, forcing ahead of them the unsaturated air that was originally within the passage, and packing this air against the cylinder walls where it is not available to mix with and support the combustion of the fuel charge. By disposing the passage eccentrically of the axis of the piston space, an unbalanced condition is produced in the piston space, causing the gases which enter therein during the working stroke to sweep laterally over the face of the piston, thereby causing an intensive turbulence within this space. This turbulence insures a prompt and intimate mixture of all the air in the piston space with the gases

therein. This turbulent condition is of marked utility when, as in an engine of the type hereinabove mentioned, the fuel is introduced in the form of impacting fuel sprays at or just before compression dead center.

Other objects and advantages will appear from the following description of an illustrative embodiment of the present invention.

In the drawings:

Figure 1 is a fragmentary axial section of an oil engine cylinder constructed in accordance with the present invention.

Fig. 2 is a sectional view taken substantially along the line 2-2 of Figure 1.

The engine cylinder selected for illustration comprises the usual cylinder proper 10 having the usual water jacket 11, and enclosing a piston 12 of well known form. In this instance the piston is provided with a convex end face 13. The cylinder is closed by a water jacketed head 14 having vertical parallel openings 15 for receiving the usual removable valve cages 16 containing the intake and exhaust valves 17 and 18.

The head 14 is internally shaped to provide an elongated chamber 19 disposed transversely of the axis of the cylinder. The top wall 20 of the chamber shown is substantially flat except for the openings 21 provided therein for accommodating the valve cages. One end of the chamber is relatively shallow the bottom wall thereof being formed by a substantially flat plate 22 formed as an integral part of the head 14, and integrally connected with the substantially flat vertical side walls 23. The other end of the chamber is relatively deep being defined by a steeply inclined end wall 24. The walls 20, 22, 23 and 24 are all water cooled. A restricted passage 25 is provided through the bottom of chamber 19 through which communication is maintained between the chamber and the piston space 26. As will appear from Figure 2 this passage is of elongated rectangular form. It extends transversely of the chamber 19 and is disposed at the junction of the bottom wall 22 with the end wall 24 adjacent one end of the chamber and at one side of the central axis of the piston space. The bottom of the head 14 is preferably concave so as to conform in general with the convex end face 13 of the piston.

It will be noted that the chamber shown is so shaped that the major portion of the air therein is disposed within the relatively deep end thereof adjacent the passage 25, the other end being relatively shallow, and of a depth only sufficient to accommodate the flat spray and to provide clearance for the valve 18. A relatively large body of air is thus provided above and to the left of the center of the passage.

Two opposed fuel injection nozzles 27 and 28 are disposed at opposite ends of the chamber in appropriate bores formed through the sides of the head 14. The nozzles shown are of the type described in my copending application Serial No. 714,266, filed May 19, 1924, and are capable of delivering substantially flat fuel sprays, without air, into the chamber. These nozzles in this instance are relatively inclined so as to insure good impact of the issuing sprays within a zone eccentrically disposed at the right of the passage 25. In order that the spray issuing from the nozzle 27 may be of sufficient length to permit full development thereof, this nozzle is preferably set back away from the end wall 24, and a recess 29 provided in this wall to clear the spray.

In operation, the fuel is injected under pump pressure, and without air, through the nozzles 27 and 28, in a sudden substantially instantaneous charge at or just before compression dead center, when the compression stroke of the piston has practically ceased and the air in the chamber is at rest. The sudden impact of the opposed sprays, thus formed, produces a dense cloud of relatively heavy fuel mist, momentarily suspended in the chamber 19 adjacent the right side of the passage 25. A relatively light fuel mist is simultaneously formed about the concentrated cloud and at the surfaces of the fuel sprays, due largely to the frictional contact of the sprays with the compressed air in the chamber. This lighter fuel mist is readily vaporized and ignited by the heat of compression and combustion sets in. The heat developed by this initial combustion permeates the concentrated fuel cloud so as to vaporize a large portion of the fuel therein and prepare the same for quick burning. Actual combustion of this fuel does not occur however until and as the same is brought into intimate contact with air in sufficient quantities to support the combustion.

Substantially simultaneously with the initial combustion the piston starts downwardly on its working stroke and the contents of the chamber, agitated by the combustion, begins to flow through the throat. During such flow the dense cloud of partially vaporized fuel is broken up by the resulting turbulence and carried toward the passage 25 where it meets and mixes with the large body of hot unsaturated air which

is simultaneously flowing toward the passage. This results in prompt combustion of the fuel charge, the major portion of the combustion occurring in the passage and piston space.

The eccentric relation between the passage 25 and piston space causes the flow through the passage to sweep laterally over the end face of the piston so as to effect an intensive turbulence within the piston space. This turbulence insures a thorough mixture of all the air in the piston space with the entering gases and consequently a complete combustion of all fuel suspended in these gases.

Various changes may be made in the embodiment of the invention hereinabove specifically described without departing from or sacrificing any of the advantages of the invention as defined in the appended claims.

I claim:

1. In an oil engine the combination of a cylinder having a piston space and an elongated chamber extending transversely thereof, said chamber being deeper at one end than at the other, a restricted passage connecting said piston space and said chamber adjacent the deeper end thereof, and means for producing a plurality of impacting fuel sprays which meet in a zone in said chamber adjacent one side of said passage.

2. In an oil engine the combination of a cylinder having a piston space and an elongated chamber extending transversely thereof, said chamber being deeper at one end than at the other, a restricted passage connecting said piston space and chamber adjacent the deeper end thereof, and means at opposite ends of said chamber for producing a pair of impacting fuel sprays which meet in a zone adjacent one side of said passage.

3. In an oil engine the combination of a cylinder having a piston space and an elongated chamber extending transversely thereof, a restricted passage connecting said space and chamber adjacent one end thereof, and means disposed at opposite ends of said chamber for producing a pair of fuel sprays therein which meet in a zone adjacent said passage.

4. In an oil engine the combination of a cylinder having a piston space and elongated chamber extending transversely thereof, a restricted passage connecting said space and chamber and eccentrically disposed with respect to the axis of said space, and means at opposite ends of said chamber for producing a pair of impacting fuel sprays which meet in a zone adjacent said passage.

5. In an oil engine the combination of a cylinder having a piston space and a chamber, a restricted passage connecting said space and chamber and eccentrically disposed with respect to the axis of said space,

and means for producing a plurality of impacting fuel sprays which meet in a zone in said chamber adjacent said passage.

6. In an oil engine the combination of a cylinder having a piston space, an unsymmetrical chamber having a large body of air eccentrically disposed therein at compression dead center, means for producing a cloud of fuel concentrated eccentrically of

said body of air substantially at compression dead center, and a restricted passage connecting said space and chamber through which said fuel and said body of air flows during the working stroke to effect a combustible mixture.

In witness whereof, I hereunto subscribe my name this 6th day of July, 1925.

OTTO A. BANNER.
